(57) **CLAIM**

The ornamental design for an oil funnel, as shown and described.

DESCRIPTION

FIG. 1 is a perspective view showing our new design for an oil funnel,

FIG. 2 is a top view thereof,

FIG. 3 is a bottom view thereof,

FIG. 4 is a front view thereof,

FIG. 5 is a rear view thereof,

FIG. 6 is a left side view thereof,

FIG. 7 is a right side view thereof,

FIG. 8 is a perspective view of another embodiment of the present invention,

FIG. 9 is a top view thereof,

FIG. 10 is a bottom view thereof,

FIG. 11 is a front view thereof,

FIG. 12 is a rear view thereof,

FIG. 13 is a right side view thereof; and,

FIG. 14 is a left side view thereof.
